UNITED STATES PATENT OFFICE.

DAVID WARREN, OF ROXBURY, MASSACHUSETTS.

GARMENT BAG.

Application filed April 27, 1927. Serial No. 187,034.

This invention relates to certain improvements in that class of garment bags which are designed to be tightly closed so as to exclude moths.

5 The objects of the present invention are to provide an improved form of closure for bags for this purpose, which is adapted to hold the mouth of the bag distended for filling purposes and the members of which 10 are constructed to be conveniently and tightly locked together so that the possibility of the entrance of moths will be prevented.

I accomplish these objects by the means hereinafter described and as illustrated in 15 the accompanying drawing in which:

Fig. 1 is a side elevation of an embodiment of the invention.

Fig. 2 is an elevation of the inner side of one of the closure members.

20 Fig. 3 is a transverse sectional view, at line 3—3 of Fig. 1, showing the closure members in open position.

Fig. 4 is a sectional view at line 4—4 of Fig. 1.

25 Figs. 5 and 6 are detail side and top views of one of the locking clasps.

Fig. 7 is a sectional view, at line 3—3 of Fig. 1, showing the closure members in closed position.

30 As shown in the drawing, a bag 10 is provided, which is of any suitable sheet material, opposite portions of which, at the mouth, are clamped between an outer plate 12 and an inner plate 13 at one side and

35 between an outer plate 14 and an inner plate 15 at the opposite side, leaving an equal portion of the material between each of the adjacent ends. Said plates are all formed from flat sheet metal. The outer plate 12

40 is bent at right angles at its top, to form a top portion 12^a and at right angles again, or reversely, to form an edge flange 12^b which depends from the top portion, thereby forming a groove or recess which extends

45 for the entire length of said plate. End flanges 12^c are also formed thereon, which meet the inner sides of the portions 12^a and 12^b so as to close the ends of said groove.

The outer plate 14 is bent at right angles at 50 its top to form a top flange 14^a and an end flange 14^b, the width thereof being such that the top portion of the plate 14 may be fitted into the groove formed in the top portion of plate 12, as shown in Figs. 4 and 7. A clasp 16 is connected by a hinge 17 to each end of the plate 12, each clasp being of an-

gular construction, so that it may be swung about the end flanges 12^c against the outer side of the plate 14, so as to enclose the ends of said plates. A spring catch 18 is 60 provided on plate 14 at each end for holding each clasp in this position, as shown in Figs. 1, 4, 5 and 6.

The inner plate 13 is provided with a ledge 20, to which several rings 21 are attached for the purpose of providing means for supporting clothing yokes and a spreader hook 22 is attached to the plate 13 at each end, said hooks being arranged to be engaged with the opposite plate 15 to hold the bag 70 distended, as shown in Fig. 3.

With the above described construction, when the bag is to be closed, the hooks 22 are disconnected and folded beneath the plate 13, a bracket 23 being provided to support 75 the free end of each hook, as shown in Fig.

2. The bag portions between the ends of the closure members are then folded inward and the closure members are brought together until the edges of the flanges of plate 14 engage the inner sides of the plate 13, and then the former is moved sidewise or upward, so that its top portion 14^a is seated within the groove of plate 12. The clasps 16 are then swung into engagement with the plate 14 at each end and locked in this position by the spring catches 18, thereby enclosing the ends of the plates and securely holding them in closed position.

I claim:

1. In a garment bag, a pair of closure members, each comprising an elongated metal plate, means for securing opposite portions of the bag at its mouth to said plates, one of said plates having a reversely 95 extending top portion at one side thereof forming a recess extending throughout its length and the other plate having its top portion arranged to be fitted into said recess to close the bag tightly and means for locking said members in closed position.

2. In a garment bag, a pair of closure members, each comprising an elongated metal plate, means for securing opposite portions of the bag at its mouth to said plates, one of said plates having its top portion extended laterally and reversely to form a groove which extends for the length thereof and having means to close the ends of said groove, and the other plate having a laterally extending top portion adapted to be fitted in said groove.

3. In a garment bag, a pair of closure members, each comprising an elongated metal plate, means for securing opposite portions of the bag at its mouth to said plates, one of said plates having a reversely bent portion at its top edge forming a groove which extends for the length thereof and the other plate having its top portion arranged to be fitted into said groove, and a clasp on one of said plates arranged to be moved to enclose the ends of said plates and hold them in engaged position.

4. In a garment bag, a pair of transverse closure members, each comprising an elongated metal plate, means for securing opposite portions of the bag to the lower edge portion of each plate in position to permit intermediate portions of the bag to be folded inward therebetween, one of said plates having a recess at its top portion extending throughout its length and arranged to receive the top edge of the other plate when said plates are engaged, and clasps on said plate arranged to enclose the ends thereof and hold them in engaged positions.
